SLIDER WINDOW EXTRUSION

Donald L. Miller, Miami, Fla., assignor to Daryl
Industries, Inc., a corporation of Florida

Filed Apr. 21, 1967, Ser. No. 6,779

Term of patent 14 years

(Cl. D13—6)

Fig. 1

Fig. 2

Fig. 3

FIG. 1 is a top plan view of a slider window extrusion, showing my new design;

FIG. 2 is a perspective view thereof;

FIG. 3 is a bottom plan view thereof.

The surfaces of the extrusion are smooth and unornamental.

I claim:

The ornamental design for a slider window extrusion, as shown and described.
